PAUL SEITZ, OF KREUZNACH, GERMANY, ASSIGNOR TO SEITZ-WERKE G. M. B. H., OF KREUZNACH, GERMANY

COIN-FREED VENDING MACHINE

Application filed October 23, 1929, Serial No. 401,704, and in Germany November 3, 1928.

The present invention relates to automatic vending machines of the type in which the goods are delivered subsequent to the insertion of a number of coins. The object of the 5 invention is to provide means for recovering from the automatic vending machine prior to the delivery of the goods, any coins which have already been inserted. Such an arrangement is necessary with automatic vending machines in which the goods are delivered 10 after the insertion of a number of coins because the purchaser may find that he is mistaken as to the number of coins in his possession and then must be able to recover the 15 coins which he has already inserted.

According to the present invention this problem is solved by providing the coin chute, in which the inserted coins are held prior to their passage to the release device and to the 20 coin collector until the complete number of coins have been inserted, with an aperture which normally is closed but can be opened by means of the action of a press button or the like provided on the exterior of the automatic vending machine and operated by the purchaser, whereupon the coins which have been 25 inserted fall into a receptacle which is accessible from the outside of the machine, whence they can be removed by the purchaser.

30 The arrangement according to the invention can further be such that the recovery of coins from the automatic vending machine is possible only before the complete number of coins requisite for the delivery of the 35 goods has been inserted but is no longer possible after the last coin has been inserted in the automatic vending machine. For this purpose, according to the invention, the coins drop on to an arm of a balance, the free 40 end of which projects into the coin chute, the balance being so adjusted that the arm is only displaced by the weight of the coins when the complete number of coins has been 45 inserted and then allows the coins to pass to the release device of the automatic vending machine and to the container in which the coins are collected.

The arrangement can be used in the case when a plurality of apertures for the insertion of coins of different values and a corre-

sponding number of coin chutes is provided, the device being operable however from a common press button or the like.

In the drawing an embodiment of the invention in a machine having two coin chutes 55 is represented by way of example.

Fig. 1 shows a side view,

Fig. 2 a front view and

Fig. 3 a partial section along the line A—A of Fig. 1.

After insertion, the coins pass into the coin chute 1 where they are in the first place retained by a stop device 2 the action of which is described more fully below. In the wall of the chute and preferably directly above the stop device 2 is provided an aperture 3 which preferably is in the form of an elongated aperture extending in a vertical direction and which is normally closed by a correspondingly shaped flap member 4 which is 70 mounted on the pivot 5 on the outer wall of the coin chute 1. By pressing the knob 6 the flap member 4 can be caused to uncover the aperture 3 if desired by the use of an intermediate gear such as a double-armed lever 75 7, the lever 7 and the flap member 4 then assuming the positions 7', 4' indicated in dotted lines in Fig. 1 and the coins in the chute fall through the aperture 3 into the receptacle 10 which is accessible from the 80 outside of the machine and from which the coins can be removed.

As shown in Fig. 2 the flap members 4 in the two coin chutes 1 are actuated by a common press button 6 by means of the lever 7 85 and a rod 8.

The coin chute 1 can be closed approximately at the level of the lower edge of the aperture 3 by means of a movable closure member 2, which after all the coins have been 90 inserted allows the coins to pass to the release device. In this case it is possible to recover the coins even after the insertion of the last of the necessary number of coins. It is preferred however for practical use to 95 arrange that the possibility of recovering coins is only present until after the insertion of the penultimate coin whereas after the insertion of the last coin the vending device immediately becomes operative. For this 100

purpose the closure member 2 in the coin chute is constituted by an arm of a balance 9. The arm 2 of this balance, which may be a weight or spring balance as desired, passes 5 into the coin chute 1 and the balance is so adjusted that the arm 2 remains in position to retain the coins until after the insertion of the penultimate coin but after the insertion of the last coin is displaced by the total 10 weight of the coins and allows the coins to pass to the delivery device, preferably operating automatically, and to the container in which the coins are collected. The balance can be adjusted as indicated in Fig. 2 15 by positioning a counter-weight or by altering the setting of a spring and thus adapted to the weight of any number of coins which has to be inserted.

I claim:—

20 1. In an automatic vending machine, a coin chute having a coin-delivery aperture in its wall, movable means normally closing said aperture, means operable outside of the machine for moving said closing means thereby 25 to open the aperture, and means for supporting coins in said chute in position to pass successively through said aperture, said supporting means being automatically shiftable under the weight of a predetermined 30 number of coins thereby to move said coins out of said position and prevent delivery thereof through said aperture.

2. In an automatic vending machine, a coin chute having a coin-delivery aperture in its wall, movable means normally closing said aperture, means operable outside of the machine for moving said closing means thereby to open the aperture, and a pivoted member extending into said chute for supporting 40 coins in position to pass successively through said aperture, said member being adapted to swing on its pivot under the weight of a predetermined number of coins thereby to move said coins out of said position and prevent delivery thereof through said aperture.

3. In an automatic vending machine, a coin chute having a coin-delivery aperture in its wall, a pivoted member normally closing said aperture, compressible means operable outside of the machine for operating said member into aperture-opening position, and a pivoted member extending into said chute for supporting coins in position to pass successively through said aperture, said member being adapted to swing on its pivot under the weight of a predetermined number of coins thereby to move said coins out of said position and prevent delivery thereof through said aperture.

60 In testimony whereof I affix my signature.
PAUL SEITZ.
